UNITED STATES PATENT OFFICE.

JOHN ALBERT ANDERSON, OF GENESEO, ILLINOIS.

ATTACHMENT FOR BEARINGS.

Application filed September 9, 1920. Serial No. 409,202.

To all whom it may concern:

Be it known that I, JOHN A. ANDERSON, a citizen of the United States, residing at Geneseo, in the county of Henry and State 5 of Illinois, have invented a new and useful Attachment for Bearings, of which the following is a specification.

It is the object of this invention to provide novel means whereby a nut on a bolt 10 may be rotated to take up wear in the part through which the bolt passes. The invention aims to provide novel means whereby a spring which imparts rotation to the bolt, as aforesaid, may be wound up and held under 15 tension.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

In the accompanying drawings:—

Fig. 1 shows in elevation a device constructed in accordance with the invention, the same being assembled with the bearing, and the parts of the bearing appearing in 35 section. Figure 2 is a plan showing one of the nuts and the rotatable member which is journaled thereon; Figure 3 is a plan showing the other of the nuts; Figure 4 is a fragmental section showing a portion of the bolt 40 and the nuts; Figure 5 is a view similar to Figure 1 but showing a modification; Figure 6 is a plan disclosing one of the nuts and a rotatable member; Figure 7 is a plan disclosing the rotatable member; Figure 8 is a 45 plan depicting one of the nuts; Figure 9 is a section showing the structure disclosed in Figure 5; Figure 10 is a plan showing the modification in the rotatable member; and Figure 11 is a section on the line 11—11 of 50 Figure 10.

As disclosed in Figures 1, 2, 3 and 4, the numerals 25 and 26 denote members through which a bolt 27 passes, the bolt having a head 28 engaging the member 25. A nut 29 55 is mounted on the threaded portion 43 of the bolt 27 and has a tubular neck 30. The bolt

27 has coarse left hand threads 44 engaging the member 26. A washer 31 is mounted on the neck 30 with a driving fit. A rotatable member 32 in the form of a plate is journaled on the neck 30 between the washer 31 and the head of the nut. The rotatable member 32 has arms 33 provided with notches 34 and openings 35. A tubular nut 36 is mounted on the threaded part 43 of the bolt 27 and has a wrench head 37 provided with a notch 38. A coil spring 39 is disposed around the tubular nut 36, the spring having hooks 40 at its ends; one hook being engaged with one of the notches 34 of one 70 of the arms 33, and the other hook 40 being engaged with the notch 38 in the wrench head 37 of the tubular nut 36. A tie, such as a piece of wire, denoted by the numeral 41 is engaged in one of the openings 35, the 75 tie being connected by an anchor, which may be in the form of a pin 42, to the part 26.

The nut 36 is rotated until it bears against the neck 30 of the nut 29, the spring 39 being put under tension, the nut 36 serving 80 as a lock nut for the nut 29. When looseness occurs between the parts 25 and 26, the spring 39 reacts and by turning nut 36 rotates the bolt 27, the parts 25 and 26 being brought together because the bolt is threaded 85 at 44 with a left hand thread into the part 26.

Passing to Figures 5, 6, 7, 8 and 9 the numerals 45 and 46 designate two members through which passes a bolt 47 having a 90 head 48 engaging the member 45. The bolt 47 has a thread 49 on which is mounted a tubular nut 50 having a wrench head 51 cooperating with the member 46. There is a notch 52 in the edge of the wrench head 51, 95 as shown in Figure 12. The numeral 53 denotes a nut on the threaded part 49 of the bolt, the nut 53 having a neck 54 on which a washer or ring 55 is fitted tightly. A member 56 is rotatably mounted on the neck 54 between the washer 55 and the body portion 100 of the nut 53, the rotatable member having a knurled flange 57 whereby rotation may be imparted readily to the said member. The member 56 has notches 58 in its edge 105 and is provided, as shown in Figure 11 with the key hole slot 59. The numeral 60 marks a coil spring surrounding the tubular nut 50. The spring 60 has hooks 61 at its ends. One of the hooks 61 is engaged in the notch 110 52 of the tubular nut 50, the other hook being engaged in the key hole slot 59 of the

- rotatable member 56. The nut 53 has a side recess 62 wherein is located a tie 64, which may be a piece of wire. One end 65 of the tie is engaged as shown in Figure 10 with the nut 53. The other end 66 of the tie may be passed into any of the notches 58 in the rotatable member. A lock nut 67 is mounted on the threaded portion of the bolt and bears against the nut 53.
10. The member 56 may be rotated to put the spring 60 under tension, and after a tension is secured in the spring, the wire or tie 64 may be engaged in the appropriate one of the notches 58. The lock nut 67 then is 15 tightened down on the nut 53 and, obviously, the tension will be held in the spring, the spring serving to rotate the nut 50 and to advance the same with respect to the member 46 as soon as any looseness occurs.
20. Referring to Figures 10 and 11, a rotatable member 70 is shown and is provided with arms 71 having openings 72. In this modification, the rotatable member 70 is divided along the line 73 and is provided with 25 outstanding fingers 74 having notches 75 in their edges. A bendable strip 76 may be used to connect the parts 74, the strip being engaged in the notches 75 and being turned over on the parts 74, as indicated at 77 in 30 Figure 11.

It is not possible to show all of the various forms which the invention may take, nor has any attempt been made to show all of the applications to which the invention may 35 be put. The forms shown will, however, constitute a useful index, directing a person skilled in the art, to many other applications which will suggest themselves without dif-

ficuity when this specification is read in connection with the drawing.

Having thus described the invention, what is claimed is:—

1. In a device of the class described, a bolt and a nut having cooperating threads; a rotatable member; means for supporting said member on the bolt for rotation independently of the threads of the bolt; means independent of the nut and bolt for holding said member releasably against rotation; and a torsion spring connecting the rotatable member and the nut.
2. In a device of the class described, a bolt and superposed nuts having cooperating threads; a rotatable member journaled on one nut independently of the threads of the bolt; means for holding said member releasably against rotation; and a torsion spring connecting the rotatable member and the other nut.
3. In a device of the class described, a bolt; superposed nuts threaded thereon; a rotatable member journaled on one nut, independently of the bolt; a torsion spring connecting said member with the other nut; a tie forming a releasable connection between the rotatable member and the first specified nut; and a lock nut on the bolt, the lock nut engaging the first specified nut.

In testimony that I claim the foregoing as my own, I have hereto affixed my signature in the presence of two witnesses.

JOHN ALBERT ANDERSON.
